J. H. SHAW.

SPRING HINGE.

No. 309,104.

Patented Dec. 9, 1884.

UNITED STATES PATENT OFFICE.

JOHN H. SHAW, OF NEW HAVEN, CONNECTICUT, ASSIGNOR TO SARGENT & CO., OF SAME PLACE.

SPRING-HINGE.

SPECIFICATION forming part of Letters Patent No. 309,104, dated December 9, 1884.

Application filed July 30, 1884. (Model.)

To all whom it may concern:

Be it known that I, JOHN H. SHAW, of New Haven, in the county of New Haven and State of Connecticut, have invented a new Improvement 5 in Spring-Hinges; and I do hereby declare the following, when taken in connection with accompanying drawings and the letters of reference marked thereon, to be a full, clear, and exact description of the same, and which 10 said drawings constitute part of this specification, and represent, in—

Figure 1, a vertical sectional view; Fig. 2, a transverse section on line xx ; Fig. 3, a transverse section on line yy ; Fig. 4, a transverse 15 section on line zz .

This invention relates to an improvement in that class of spring-hinges in which the two parts of the hinge are constructed with ears at their respective ends to set together, and so as 20 to leave a space in the central part of the knuckle, into which space a spiral spring is introduced around the pintle, one end of the spring to take a bearing upon one leaf and the other end upon the other leaf, the action of 25 the spring being to turn the two leaves together or open them, as the case may be, and according to the action of the spring, the object being to provide a means of adjustment for the spring, or its entire release, without 30 longitudinally moving the pintle; and it consists in the construction as hereinafter described, and more particularly recited in the claim.

A B represent the two ears of one leaf of 35 the hinge, and C D the two ears of the other leaf, and in the usual form of construction, so as to leave a space between the intermediate ears, A B, for the introduction of the spring. These ears are bored to receive the pintle, 40 also in the usual manner. The pintle is made in two parts, E F, and, as here represented, the part E is the top and F the bottom. The part F is constructed with a shoulder, a , to abut against the ear D, the body of the 45 pintle fitting the two ears B D. The upper end of the part F is made tubular. It is inserted upward through the ear D into the ear B. The other part, E, is of like shape, so as to pass through the two upper ears, A C, and 50 with a shoulder, b , to rest upon the top of the

ear C. This part E extends downward, its lower end, d , fitted to enter the part F, as shown, and so that the part F forms a bearing for the lower end of the part E. The end d , within the pintle F, is constructed with an annular groove, e . A screw, f , is introduced through the ear B of one part of the hinge into the tubular part F, and so that its inner end will enter the annular groove e in the part E. This screw f couples the part F of the 60 pintle with one part of the hinge, and also prevents the part E from being withdrawn. Through the ear C—that is, the ear of the other part of the hinge—a pin, h , is introduced to enter a corresponding hole in the part 65 E of the spindle, and so as to couple this second part of the hinge with the part E of the pintle. Thus it will be seen that the part F of the pintle is coupled with one part of the hinge and the part E with the other part. On the 70 pintle, between the ears A B, is a longitudinal groove, i . Around the pintle, between the ears A B, a helical spring, H, is introduced, one end, l , turned inward to enter the groove i in the part E of the pintle. The other end, 75 m , is arranged to bear upon the leaf of the hinge with which the part F of the pintle is engaged. By this usual arrangement of the spring one end of the spring bears upon one leaf directly and the other end upon the pin- 80 tle which is engaged with the other leaf.

The head I, or exposed portion of the part E, is constructed of polygonal shape, as at n , or may be with holes p , by which that part of the pintle may be turned by applying a wrench 85 to the polygonal portion n , or a lever into one of the holes p .

To adjust the spring the pin h is removed and the part E of the pintle turned until the required tension of the spring is attained. Then 90 the pin h is introduced to enter the corresponding hole in the part E. The turning of the part E winds the spring, and the introduction of the pin h couples the pintle with its part of the hinge, holding the spring under tension. 95

The method of turning the pintle so as to wind the spring is a well-known device, so also is the longitudinal groove i in the pintle, which enables the pintle to be introduced at one end, pass down to the opposite end of the 100

hinge, the groove *i* passing over the end *l* of the spring.

By making the pintle in two parts, as described, and extending the one part into the other, and introducing the screw or pin *f* through the one part of the hinge into the said other part of the pintle, and into an annular groove on said one part, the one part of the pintle is permitted to turn on the other, yet accidental separation of the two parts is prevented. If, however, at any time it is desirable to separate the two parts of the hinge, it is only necessary to remove the screw or pin *f* and the pin *h*. Then the pintle may be withdrawn. This construction of pintle also makes a strong and firm joint, and the hinge, as a whole, is not liable to derangement.

I claim—

In a spring-hinge substantially such as described, the combination of the two parts of the hinge, each constructed with ears, which set together form the knuckle, the part *F* of

the pintle introduced through the ears at one end and secured to one part of the hinge, its inner end of tubular shape, the part *E* of the pintle introduced through the other end and detachably secured to the other part of the hinge, its inner end constructed to enter the tubular portion of the part *F* of the pintle, and also constructed with an annular groove, the pin *f*, which secures the one part of the hinge to the part *F* of the pintle, arranged to enter the said annular groove in the part *E* of the pintle, and a spring around said pintle, one end arranged to take its bearing in the part *E* of the pintle, the other to take its bearing on the part of the hinge with which the part *F* of the pintle is engaged, substantially as described.

JOHN H. SHAW.
